UNITED STATES PATENT OFFICE.

ANTON T. LUECKENBACH, OF NEENAH, WISCONSIN.

VENTILATED TOILET.

Application filed April 3, 1922. Serial No. 548,896.

To all whom it may concern:

Be it known that I, ANTON T. LUECKENBACH, a citizen of the United States, residing at Neenah, county of Winnebago, and 5 State of Wisconsin, have invented new and useful Improvements in Ventilated Toilets, of which the following is a specification.

This invention relates to a water closet ventilator.

- 10 Objects of this invention are to provide a ventilated water closet in which a vertical flushing pipe, such as that associated with the usual bowl, may be used; to provide a ventilated water closet of such construction 15 that great flexibility of attachment, or freedom in choice of positions of the ventilating pipe is permitted; and to provide a ventilated closet in which the bowl very closely approximates the standard bowl.
- 20 Further objects are to provide a bowl for a ventilated water closet which may be readily made in factories equipped for the usual types of bowls; to provide a bowl in which the hinges for the seat and cover may be 25 attached in the usual manner; and to provide means for adapting a standard bowl for attachment to a ventilating pipe.

Embodiments of the invention are shown in the accompanying drawing, in which:—

- 30 Fig. 1 is a plan view of a bowl, with the cover shown in dot and dash lines, and with the flushing pipe and ventilating pipe broken off.

Fig. 2 is a side elevation, partly in section, of the structure shown in Fig. 1.

Fig. 3 is a view of a modified form.

Fig. 4 is a view of the attachment shown in Fig. 3.

Fig. 5 is a view of a portion of the under 40 side of the seat.

Figs. 1 and 2 will first be described. The bowl 1 is provided with usual vertical flushing pipe 2, seat 3, hinge supports 4. The seat hinges 6, as well as the cover hinges 7, 45 (the cover being omitted), are pivoted to the hinge supports 4. Between the rear inner margin of the bowl and the flushing pipe 2, an upwardly bulging member 8 having an interior cavity 9, is provided and is 50 formed integrally with the bowl 1. The cavity 9 opens outwardly just below the rear portion of the seat 3 as indicated at 10. It may be found desirable to form a slight depression or channel 11 in the upper rear face 55 of the bowl. The rear portion of the mem-

ber 8 has a pair of angularly disposed faces 12 through which pass ducts, or openings 13. These openings 13, it will be seen, are directed diagonally outwardly on each side of the flushing pipe 2.

The ventilating pipe 14 may enter, and be secured in, either of these openings, while the unused opening may be closed by a suitable plug or cap. This ventilating pipe is usually connected with a flue or ventilating 60 passageway. The pipe 14, as may be seen from Figs. 1 and 2, may extend either rearwardly, upwardly, or downwardly, for, by the construction thus far described, great 65 flexibility or freedom of attachment of the 70 ventilating pipe is secured.

The seat 3 is supported by the usual cushioned members 15, and is thus spaced a slight distance from the bowl. The hinges 6 are extended, curving about the lower rear portion of the seat, as indicated at 16, and gradually merging into the rearwardly extending, parallel members 17. This curved portion is provided with a downwardly extending flange 18 which extends a slight 75 distance into the bowl and in close proximity to the inner, upper peripheral portion thereof. The parallel members 17 are similarly provided with a flange 19 extending downwardly into the channel portion 11. 80 These last described flanges are preferably integral with the flanges 18 and form a continuation thereof. The flanges, the lower surface of the rear portion of the seat, and the channel 11, form a continuation of the 85 opening 10 and place the cavity 9 in communication with the interior of the bowl adjacent its rear upper portion.

It will readily be seen that, when the 90 ventilating pipe 14 is connected with a flue or chimney, a draft is created within the bowl which draws air under the front portion of the seat and rearwardly into the cavity 9, thereby removing any fumes or odors. Therefore, any odors that are produced in the bowl while it is in use and before it is flushed, are continuously removed 100 and do not pass outwardly into the room.

Fig. 3 shows a modified form in which a separate and independent member 20 is 105 cemented to the upper face 21 of the usual type of bowl. This member is substantially similar to the member 8 previously described, and is provided with an internal cavity 22 into which opens the entrance 110

duct 23. A pair of openings 24 is adapted to receive the ventilating pipe 14 in a manner similar to that previously described.

In this form of the invention a flushing pipe 24 having an elbow portion 25 may be provided. The horizontal portion of the flushing pipe may, thereupon, enter the rear of the bowl, and may be secured thereto in any desired manner.

10 It is to be understood, that either form of bowl may be provided with either a straight, vertical flushing pipe, or with an elbowed flushing pipe, as the particular form of ventilator gives great freedom of choice.

15 It will be seen that a ventilated toilet has been provided in which all odors are removed; in which great flexibility of attachment of the ventilating pipe is attained; and in which either a straight, vertical flushing pipe, or an elbowed flushing pipe may be provided.

I claim:

1. A toilet comprising a bowl, a seat therefor, an odor receiving member positioned to the rear of said seat and having an opening communicating with the space below said seat, hinges for said seat independent of said odor removing member and supported from said bowl, and flanges

formed integrally with said hinges and forming a flaring continuation of said opening.

2. A toilet including the combination with a bowl, a seat spaced therefrom, and an odor receiving member positioned at the rear of the seat and provided with an opening communicating beneath the seat with the interior of the bowl, of a hinge connecting the seat to the bowl and provided with a hasp registering with said opening and extending partially around the under side of the seat, and a flange integral with the hasp and projecting downwardly within the margin of the bowl and conforming thereto.

3. A toilet including the combination with a bowl, a seat, a ventilating member provided with an opening communicating beneath the seat with the interior of the bowl, and a set of hinges connecting the seat to the bowl, of flanges secured to the under side of the seat and arranged to register with said opening and to project from said seat into the bowl, said flanges being extended from said opening partially around the bowl in conformity with the inner and upper margins thereof.

ANTON T. LUECKENBACH.
